UNITED STATES PATENT OFFICE.

CHARLES H. BREERWOOD, OF ALLENTOWN, PENNSYLVANIA, ASSIGNOR TO FULLER-LEHIGH COMPANY, A CORPORATION OF PENNSYLVANIA.

PULVERIZING MILL.

Application filed March 7, 1924. Serial No. 697,543.

To all whom it may concern:

Be it known that I, CHARLES H. BREERWOOD, a citizen of the United States, residing at Allentown, in the county of Lehigh, State of Pennsylvania, have invented certain new and useful Improvements in Pulverizing Mills; and I do hereby declare the following to be a full, clear, and exact description of the invention, such as will enable others skilled in the art to which it appertains to make and use the same.

This invention relates to pulverizing mills of the type set forth in the U. S. Letters Patent Nos. 849,779; 922,468; 1,039,721 and 1,358,837, issued to James W. Fuller, and known as the Fuller mill. This type of mill embodies in its construction a grinding or pulverizing ring in which the material is reduced to a finely divided state by means of appropriate grinding devices, usually a plurality of balls. The grinding ring forms a raceway for the grinding balls and the latter are propelled about the raceway by pushers mounted on a yoke, in turn connected to a power driven shaft. This general construction is illustrated, for example, in U. S. Letters Patent No. 1,358,837. In this particular type of mill, two grinding balls are employed with corresponding pushers to propel them, mounted on a pair of yoke arms. Two other yoke arms carry a pair of plows which are adjusted to operate in the grinding ring and which are arranged symmetrically with the grinding balls about the yoke. Each of these plows is provided with a forwardly projecting, downwardly extending inclined surface which serves to elevate the material picked up by the plow to the region above the grinding ring where there are lifting devices, such as a set of lifting blades, supplemented by a superimposed fan, for carrying the pulverized material to the upper part of the mill, where it is floated against a screen for separation of the fine from the coarser particles, or, as in another type of mill, carried into air currents for ultimate separation by an air separator.

The present invention relates particularly to an improvement in the plow which operates in the grinding ring to elevate the pulverized material above the ring and into the zone of action of the lifting devices and fan. Where constructed as shown, for example, in U. S. Letters Patent, No. 1,358,837, the

plows have been found in practice to be ineffective for preventing the accumulation of a certain amount of the material which banks or packs around the grinding ring out of range of action of the grinding balls for reduction to pulverized form, and also out of the path of the plows for elevation to the upper regions of the mill where the coarse, unground particles would again find their way back to the grinding ring for pulverization. This condition introduces a power loss, in that additional power is required to drive the grinding balls and plows against the resistance of the packed material in the ring, and furthermore, reduces the output of the mill.

An object of this invention, therefore, is to provide means associated with the grinding elements to prevent this accumulation of unground, partially ground, or fine packed material in the grinding ring of the mill. Such means is in the form of a plow positioned between a pair of grinding elements and constructed and arranged to elevate the pulverized material from the grinding ring to superjacent lifting devices, and at the same time, to pick up and deposit in the path of the succeeding grinding elements, the coarse or unground material left by the preceding grinding element, which coarse particles are then subjected to pulverization and eventual elevation from the grinding ring to the lifting devices above. In this way, the gathering of dead, packed material in the ring is prevented and the mill can be operated with the expenditure of less power and with an appreciable increase in output.

The means with which the plow is provided to effect the distribution and disposition of material as described, consist of a pair of inclined surfaces, one of which is adapted to elevate the material above the grinding ring and into the zone of action of the lifting devices, and the other of which has an extension which runs to the rear of the plow providing a passageway for the material past the plow, from which it is deposited in the path of the next succeeding grinding device. Additional features of the invention with reference to constructional details will be brought out in connection with the description of the accompanying drawing, in which—

Fig. 1 is a sectional view in elevation of

a Fuller mill of the type illustrated in U. S. Letters Patent No. 1,358,837,

Fig. 2 is an enlarged view in elevation of the yoke, showing the pushers and plows, lifting devices and fan in superimposed relation, all mounted on the yoke,

Fig. 3 is a plan view of the arrangement shown in Fig. 2,

Fig. 4 is an enlarged plan view of the improved plow constituting the subject matter of this application,

Fig. 5 is a side view of the plow shown in Fig. 4, and

Fig. 6 is an end view of the plow.

The details of construction of the mill illustrated in Fig. 1, and its operation, will be found to be fully described in U. S. Letters Patent, No. 1,358,837, and, since, the present invention concerns merely the plow, but brief reference will be made to the mill construction. The mill as shown in Fig. 1 has an outer sectional casing 7 in which material to be pulverized is introduced through a feeder 8. Mounted in appropriate bearings and extending through the mill is a shaft 9 which supports a yoke 10 and is driven by a pulley 11 connected as by means of a belt, not shown, to a source of power. At approximately the mid-point of the mill, is a grinding ring 12 which forms a raceway for the grinding balls 13. The grinding balls are projected through the grinding ring by means of pushers 14 and, in the arrangement shown, there are two grinding balls with 35 a pusher for each, the pushers being mounted on opposite yoke arms 15. In symmetrical arrangement with the balls and pushers are two plows 16 mounted on opposite yoke arms 17. The number of grinding balls and plows and their arrangement is, of course, unessential so far as the present invention is concerned, and may be varied in accordance with the dictates of proper design for any given set of conditions, or requirements of the mill. For example, instead of having two grinding balls with two pushers, four such balls might be employed with one or more plows situated between a pair of balls, or the plows might themselves be used as 50 pushers to propel the balls while functioning as plows, which changes in the mill assembly will be understood without further illustration.

Mounted on the yoke 10 above the grinding ring are lifting devices consisting of a plurality of lifting blades 18 and above these also mounted on the yoke 10 is a fan made up of a plurality of fan blades 19, which lifting devices and fan progressively raise 60 the material from a position above the grinding ring to the screen 20 through which it is floated, and the coarse particles separated from the fine. The fine material after screening, enters the outer space 21 and 65 gravitates to the lower receiving chamber 22

where it is discharged through the spout 23. The details of construction of the plow constituting the particular subject matter of this invention, are illustrated in Figs. 4, 5 and 6, to which reference will now be made.

The plow has a body portion 24 and a forwardly projecting or extending portion 25. The body portion 24 is hollowed out to reduce weight as shown at 26, and is provided with a hole 27 for receiving a vertical pin 28, projecting upwardly from the yoke arms 17 and by which the plow is supported secured on the yoke arms. In place of forming the extension 25 with a single inclined surface for picking up the pulverized material in the grinding ring and elevating it to the zone of action of the lifting devices, the present invention provides a plow, the extension 25 of which has a pair of inclined surfaces 29 and 30 separated by a substantially vertical partition wall 31. The inclined surface 29, which is the inner surface, considering the plow in its operative position in the grinding ring, acts to pick up the pulverized material from the ring and to elevate it into the zone of action of the lifting devices 18, which in turn, still further elevate the material into the region of operation of the fan. At the outer side 32 of the plow the wall is cut away so as to provide a shelf-like surface 30' which is a continuation of the surface 30 and extends to the rear end of the plow. The inclined surface 30 serves to pick up the material and lead it to the other surface 30', over which the material moves past the plow, until it is deposited in the path of the following grinding ball for pulverization. Instead of cutting away the entire wall so as to provide the surface 30' the wall may be formed with a channel 33 of which the surface 30' forms the lower side wall, this channel extending from the front to the rear and providing a passageway for the material past the plow. The inclined surface leads to this channel so as to introduce the material into it and the material then passes to the rear of the plow as before. In the drawings the plow is shown as having a channel 33 in its outer wall, but the construction of the other form in which the wall is entirely cut away will be readily understood. After the material has been deposited in the path of the following grinding ball and has been acted upon by the ball, it is picked up by the next plow and elevated by means of the inner surface 29 to the lifting device and fan for ultimate projection through the screen 20 and separation, any coarse particles which are retained by the screen being deposited again in the grinding ring by gravity. As before noted, the pair of inclined surfaces 29 and 30, together with the extension 30', serve to keep the grinding ring clear of accumulating material by keeping it in active circulation

after deposit in the grinding ring for pulverization, and this effects a saving in power and increases the output of the mill.

I claim:

5. 1. In a pulverizing mill, having a grinding ring, grinding devices operating in said ring and superjacent lifting devices, a plow of the character described positioned between a pair of grinding devices, and embodying means for elevating the pulverized material to the zone of action of the lifting devices and means for picking up coarse or unground material lying in the grinding ring and depositing it in the path of the succeeding grinding device.
2. In a pulverizing mill having a grinding ring, grinding devices operating in said ring and superjacent lifting devices, a plow of the character described positioned between the grinding devices, said plow having inclined surfaces, one of which is adapted to elevate pulverized material from the ring directly to the zone of action of the lifting devices, and another of which is adapted to pick up coarse or packed material left by the preceding grinding device for deposition in the path of the next succeeding grinding device, substantially as described.
3. In a pulverizing mill having a grinding ring, grinding devices operating in said ring and superjacent lifting devices, a plow of the character described positioned between the grinding devices, said plow having a pair of inclined surfaces, one for elevating pulverized material from the ring, directly to the lifting devices, and the other for conducting the residual material past the plow and depositing it in the path of the succeeding grinding devices for pulverization and eventual elevation to the lifting devices, substantially as described.
4. The combination with a pulverizing mill having a grinding ring, grinding devices operating in and lifting devices situated above said ring, of a plow having a pair of inclined surfaces and being provided with a channel, one of said surfaces being adapted to lift pulverized material from the ring into the region of operation of said lifting devices, and the other of said surfaces communicating with said channel, substantially as, and for the purposes, set forth.
5. The combination with a pulverizing mill of a plow, having a pair of forwardly and downwardly extending inclined surfaces and being provided with a channel, one of said surfaces leading into said channel, substantially as described.
6. The combination with a pulverizing mill of a plow of the character described, having a pair of forwardly and downwardly extending inclined surfaces, separated by a substantially vertical partition, said plow being provided with a passageway for material along its side, which terminates in one of said inclined surfaces, substantially as described.
7. The combination of a pulverizing mill having a grinding ring and grinding devices operating in said ring of a plow having a pair of forwardly projecting and downwardly extending inclined surfaces separated by a substantially vertical partition wall, one of said surfaces being adapted to elevate material above the grinding ring, the plow being provided with a channel along its side terminating in the other of said inclined surfaces which provides a passageway for material between the ring and the plow, substantially as described.
8. The combination with a pulverizing mill, having a grinding ring, grinding devices operating in said ring and superjacent lifting devices of a plow of the character described, having a pair of forwardly projecting and downwardly inclined surfaces separated by a partition wall, one of said surfaces being inwardly inclined and adapted to elevate material into the zone of action of the lifting devices, the outer surface of the plow being provided with a channel and the other of said inclined surfaces curving outwardly into the channel, substantially as described.
9. The combination with a pulverizing mill of a plow, having a forwardly and downwardly extending inclined surface at its front end and having its outer side wall cut away so as to provide a shelf-like surface over which the material is moved past the plow as the latter moves, this shelf-like surface communicating with the surface first-named.
10. A plow for use in a pulverizing mill, having a grinding ring, grinding devices operating therein, and lifting devices situated above said ring, which comprises a body portion, a forwardly and downwardly inclined surface located near its front end, and a shelf-like surface formed on the outer wall of the body portion and extending to the rear end of the plow, this surface communicating at its forward end with the inclined surface.
11. A plow for use in a pulverizing mill, having a grinding ring and grinding devices operating therein, which comprises means located at the front of the plow for picking up material, and means located along the outer side wall of the plow for conducting this material past the plow and depositing it in the path of the next succeeding grinding device.

In testimony whereof I affix my signature.

CHARLES H. BREERWOOD.
